CENTRIFUGAL CASTING MACHINE

William D. Sargent, New York, N. Y., and William A. Geisler, Newark, N. J., assignors, by mesne assignments, to Durafer (Inc.), Dover, Del., a corporation of Delaware

Application June 11, 1931, Serial No. 543,511

8 Claims. (Cl. 22—65)

- The present invention relates to devices for moulding molten metal in a centrifugal machine and embodies, more specifically, an improved form of centrifugal mould wherein the metal is cast in a centrifugal mould without the use of a core. 5 More particularly, the invention relates to centrifugal moulding mechanism, wherein molten metal is introduced into a centrifugal mould which is rapidly rotated about a vertical axis, 10 the metal being directed into the mould matrix in order that the centrifugal action of the mould may cause the metal to flow uniformly therein and harden during the continued rotation of the mould, thus dispensing with the use of a core. 15 Recently developed moulding mechanisms have provided rotating permanent moulds, wherein permanent cores are utilized, these cores being removed when the metal solidifies to permit the cast article to be removed from the mould. 20 To simplify the moulding mechanism, as well as the moulding operation, the present invention has been designed and an object thereof is to provide a centrifugal permanent mould which functions without the use of a core. 25 A further object of the invention is to provide a mould of the above character having means carried thereby to introduce the molten metal into the matrix of the mould during rotation thereof. 30 A further object of the invention is to provide in a mould of the above character, means for effectively removing the casting from the mould. In accordance with the invention the interior of the mould is provided with a recess, the width 35 of which determines the axial dimensions of the article cast and the depth of which determines the radial dimension of the article cast. Accordingly, it is a further object of the invention to provide for centrifugal casting in a mould 40 in which the dimensions of the article are determined by the interior of the mould and also to provide for the throwing out of excess metal from the mould. This object is attained by leaving the top of the mould open and permitting the 45 excess metal to be thrown out through such opening under centrifugal action after the article has been formed of predetermined thickness. 50 A further object of the invention is to provide in a centrifugal casting machine in which the mould rotates on a vertical axis, a bottom plate for the mould in combination with means for raising and lowering the bottom plate into and out of engagement with mould, means for securing the bottom plate to the mould when engaged therewith, during the casting operation, 55 and means movable with the bottom plate for rotating the mould. More particularly, in the preferred embodiment the object is to provide an electric motor mounted with the plate and movable therewith for rotating the plate and mould when the two are engaged. 5 A further object of the invention is to provide electric means consisting of an electromagnet for coupling the plate and mould during casting. 10 A further object of the invention is to provide a counterbalance for the driving motor and plate whereby they may be raised and lowered into and out of engagement with the mould with minimum expenditure of power from an independent source. 15 In accordance with the improved method of casting metal is introduced into the mould centrally thereof and thence thrown out radially to the mould or matrix, the centrifugal force exerted on the metal by the rotating mould causing the same to flow into the recess. To direct the 20 metal radially as thus poured the bottom plate of the mould is preferably formed with a conical deflector from which extend radiant ribs preferably curved to assist in the proper distribution of the metal. 25 With a view to describing the invention more fully, reference will now be made to the accompanying drawings, wherein: 30 Figure 1 is a sectional view in elevation, taken on line 1—1 of Figure 2, and looking in the direction of the arrows. 35 Figure 2 is a plan view of the device shown in Figure 1. Figures 3 and 4 are fragmentary detailed sectional views of the supporting rollers for the mould taken on the plane indicated by the lines 3—3 and 4—4, respectively, of Figure 2 and looking in the direction of the arrows. 40 Referring to the drawings the operative parts of the machine may be mounted on a vertically disposed hollow base *a* at the top of which are supported a series of spaced rollers *b* and *c* to carry the rotatable table *d* for the mould as will later appear. Some of these rollers *b* may have their axes inclined and engage the table *d* at an angle so as to support the load effectively and also contribute to thrust resistance. The other rollers *c* may be supported on horizontal axes and engage a peripheral flange *d'* at the lower edge of the table *d*, a bead *c'* on these rollers engaging the edge of the flange *d'* to resist thrust. The table *d* has secured thereto a ring *e* on which rests loosely the mould *e*. The mould is formed with a horizontal circular flange *e'* at the outer edge of which is a lip *e''* for engagement with a 45 50 55

shoulder e^6 on the ring e^3 . The engagement of the circular lip e^5 with the shoulder e^6 holds the mould centered. At the inner edge of the ring e^3 is secured a ring e^2 of non-magnetic material 5 such as brass to prevent magnetic leakage from the magnet hereinafter described. The top edge of the mould may have secured thereto or formed therewith a ring e' of smaller diameter than the mould, the ring serving as a retaining wall for 10 the metal and determining the radial thickness thereof. The metal may be introduced into the mould through the open upper end thereof in any suitable manner, there being illustrated for convenience a traveling ladle f , the discharge of 15 metal therefrom being controlled, as by some suitable valve such as f' . The table d supporting the mould e also supports a circular baffle g spaced from the table and in proper relation to the top flange e' of the mould, the purpose of the baffle g 20 being to confine and deflect any surplus metal that is thrown out of the mould.

The bottom plate for the mould is illustrated at h . This plate is adapted to be raised into engagement with the mould and secured thereto during casting and lowered away therefrom with the casting after the operation is completed. On 25 this bottom plate is preferably formed, in accordance with the invention, a central deflector h' illustrated as a cone. Extending outwardly 30 from this deflector h' are a plurality of ribs h^2 which themselves may be curved to disperse and direct the metal to the periphery of the mould and into the recess in the periphery formed by the flange e' . The action of the cone and ribs is 35 to cause the metal to flow outwardly and into the matrix of the mould with uniformity and to take a generally tangential direction when building up in the matrix, thereby better assuring a homogeneous, dense casting. The edge of the plate h 40 is preferably tapered as at h^3 for snug engagement with a tapered ring e^2 carried with the mould so that when the plate is brought into operative relation to the mould a secure union may be effected.

While the invention in its broader aspects is 45 not to be limited to the particular means used for securing the bottom plate to the mould during casting, improved electromagnetic devices for accomplishing this both simply and expeditiously 50 are shown. Referring to Figure 1 there is illustrated a vertically movable ram i adapted to be raised and lowered by any suitable power means such as an electric motor k geared operatively with the ram as through shafting k' and a pinion k^2 and rack i' , the latter being illustrated in 55 dotted lines but quite evident to the skilled mechanician. On the ram is mounted a motor l having a vertically disposed armature concentric with the axis of the mould e . The motor shaft l' of this motor l supports an electromagnet l^2 which 60 may be generally circular in form and on this electromagnet is supported the plate h . The magnet coil is indicated at l^3 . The invention is not concerned with the details of the electrical construction and connections it being sufficient 65 that suitable wiring be provided to control the operation of the motor l and to energize the magnet coil l^2 when and as desired, while permitting vertical movement of the motor and the coil 70 with the ram. Electrical connections for the coil are indicated diagrammatically at l^4 .

To counterbalance the weight of the motor l and associated parts as described there has been shown a weighted ring m supported by cables m' extending over pulleys a' and connected to 75

the ram. The pulleys a' may be journaled in brackets secured to the base a . This counterbalance is such as to enable all of the parts to be raised and lowered with minimum power by the motor k .

The method of casting will now be described. The motor k will be operated to raise the ram and its parts until the plate h is engaged with the ring e^2 . When the coil l^3 is energized the magnetic field will effectively couple the rotor l^2 , 10 plate h , mould flange e^4 and ring e^3 . With the parts thus coupled rotation of the armature l' will impart rotative movement to all of the interconnected parts which, as pointed out hereinbefore, are supported rotatably by the bearing of 15 the table d on the rollers b . Metal introduced centrally into the mould along its axis will be thrown out radially along the plate, the action being assisted by the cone h' and ribs h^2 and the metal will build up in the recess of the periphery of the mould e until it extends beyond the 20 face of the retaining flange e' whereupon excess metal will be thrown out of the central opening against the baffle g . The casting being completed 25 rotation of the motor l may be stopped, the coil l^3 deenergized and the motor k operated to pull the plate h downwardly away from the mould or to permit gravity to do so depending on the balance 30 of the parts. The casting will drop with the plate since the plate constitutes the other confining wall for the recess in the mould.

The excess metal thrown from the mould and deflected downwardly by the baffle g may run off of the table d within the shield g' which is formed with openings g^2 for the escape of any such metal. 35

It will be evident that the course of the metal under the influence of centrifugal force is such that it will build up in the recess from the bottom plate until its upward travel is checked by the circular flange e' . The speed of rotation is such 40 as to create constantly a centrifugal force sufficient to cause this continuous building up from the bottom plate to the flange. When the recess is thus completely filled with metal its thickness from the bottom edge to the top will be substantially uniform, the speed of rotation of the mould being such as to accomplish this desired condition. Any excess metal will travel over the inner edge of the flange e' and be thrown outwardly by centrifugal force. Thus, under practical 45 operating conditions of speed it is possible to cast a ring of predetermined dimensions, the distance between the bottom plate and the flange e' determining the axial dimension, and the width of the flange e' determining the radial dimension.

From the description given it will be understood 50 that the parts considered in combination are simple in construction, effective in action to facilitate the quick and uninterrupted casting without a 55 core of circular articles the cross sectional form and dimensions of which will depend on the periphery of the mould. The introduction of the metal centrally of the mould along its axis will insure its proper dispersion under the action of 60 centrifugal force within the mould and the building up of the article to be cast in the periphery of the mould in a dense homogeneous structure. The comparatively few number of parts result 65 in highly efficient and economical operation.

As indicated hereinbefore changes in the construction of some of the parts from similar functions may be made without departing from the invention.

What we claim is:

1. A vertical axis rotatable mould having a peripheral moulding recess formed with a shoulder which defines the axial and radial dimensions of the casting and having the interior thereof open, and a circular baffle mounted to rotate with said mould and arranged in the plane of the top of the mould to catch and redirect overflow from said mould.
- 10 2. A vertical axis rotatable mould having a peripheral moulding recess formed with a shoulder which defines the radial thickness of the casting and having the interior thereof open, said mould having a removable bottom, a top opening in the mould through which metal is received adjacent the axis of the mould and a circular baffle rotatable with the mould arranged in the plane of the mould top to deflect overflow from the mould.
- 15 3. Casting machine, comprising a mould, means to mount the mould rotatably on a vertical axis, a table mounted on a rotatable motor, means to secure the table to the mould, a counterweight to counterbalance the weight of the rotatable motor and table, and independent means by which to apply power to raise and lower the rotatable motor and table.
- 20 4. Casting machine, comprising a mould, means to mount the mould rotatably on a vertical axis, a plate mounted on a rotatable motor, electro-magnetic means to secure the plate to the mould, a counterweight to counterbalance the weight of the rotatable motor and table, and independent means by which to apply power to
- 25 5. In a casting machine a mould, means to support the mould on a table for rotation about a vertical axis, said table having a central aperture, exposing the bottom of said mould a bottom plate adapted to be received in said aperture for the mould and electromagnetic means to couple the mould and bottom plate releasably.
- 30 6. In a casting machine a mould, means to support the mould on a table for rotation about a vertical axis, said table having a central aperture, exposing the bottom of said mould a bottom plate adapted to be received in said aperture for the mould, electromagnetic means to couple the mould and bottom plate releasably, and an electric motor magnetically coupled to the said bottom plate to rotate the plate and mould.
- 35 7. A rotatable coreless mould adapted to rotate upon a vertical axis and formed with a peripheral recess defining the axial radial dimensions of the casting and means to introduce metal into the recess, and an annular baffle rotatable with the mould surrounding the top of said mould to deflect overflow therefrom, whereby an excess of material may be placed in the mould and subsequently overflowed to assure a radial casting dimension equal to the depth of the peripheral recess.
- 40 8. In a vertical centrifugal casting machine, a mould, a rotating table to which said mould is secured, a conical guard carried by said table of greater diameter than the mould and substantially in a plane with the top of said mould to deflect flying particles downwardly on said table, and a second stationary guard around said table adapted to deflect particles thrown from said table.

CERTIFICATE OF CORRECTION.

Patent No. 2,009,025.

July 23, 1935.

WILLIAM D. SARGENT, ET AL.

It is hereby certified that error appears in the printed specification the above numbered patent requiring correction as follows: Page 1, first column, line 19, for "moud" read mould; line 53, after "with" insert the; page 3, second column, line 17, claim 7, after "axial" insert and; line 18, same claim, strike out "and" before "means"; and that the said Letters Patent should be read with these corrections therein that the same may conform to the record of the case in the Patent Office.

Signed and sealed this 15th day of December, A. D. 1936.

Henry Van Arsdale
